DISTILLATION PRODUCT

Frank H. Bergeim, Leonia, N. J., assignor to The
Barrett Company, New York, N. Y., a corpora-
tion of New Jersey

No Drawing. Application October 3, 1930,
Serial No. 486,278

3 Claims. (Cl. 196—149)

My invention relates to a product obtained from a coal tar derived by the carbonization of coal at low temperatures and to the products obtained by said process.

5 The destructive distillation of coal at low temperatures, that is, at temperatures of about 400° to 600° C. or up to 800° C., results in the production of coal tars which in many respects are very different from coal tars obtained by the destructive distillation of coal at higher temperatures, for example at from 1000° to 1200° C., as in the ordinary by-product coke oven practice. Two to three times as much tar is produced by the treatment of coal at low temperatures and the tar 10 contains substantially no solid aromatic compounds and almost no free carbon. Furthermore, the low temperature tars are of lower specific gravity than the high temperature tars. It is generally considered that the constituents of low 15 temperature tars differ from those present in tars resulting from the destructive distillation of coal at high temperatures in that the materials have not been subjected to high temperatures and therefore they have not undergone chemical decomposition and rearrangement to the same extent.

I have discovered that products having novel and valuable characteristics are produced by subjecting the aforementioned low temperature tar to fractional distillation under a vacuum. I have found that the products of vacuum distillation of low temperature tar differ not only from the products of low temperature tar distillation at atmospheric pressure, but also from the products of vacuum distillation of ordinary high temperature tar.

The result of vacuum distillation of coal tar, whether produced by high temperature or low temperature distillation of coal, is to decrease the degree of decomposition of the products undergoing distillation by reason of the fact that the temperature to which the materials are subjected in effecting their distillation is materially lowered. However, the vacuum distillation of tar originally obtained by the distillation of coal at high temperatures gives no indication of the characteristics of the material which may be obtained by the vacuum distillation of low temperature tars. The organic compounds present in the various 40 fractions obtained by fractional distillation under a vacuum are probably different from those obtained by distillation at atmospheric pressure because of the fact that the tar is not heated to such a high temperature during the distillation 45 operation.

The principal object of my invention is to provide a new process for treating low temperature tars by means of which new products are obtained.

A further object of my invention is to produce 5 new and valuable coal tar products having characteristics which distinguish them from coal tar products derived by other methods of production.

The term "low temperature tar" as employed throughout the specification and in the claims 10 refers to the condensate from volatile products derived by the carbonization of coal at temperatures of from about 400 to 600° C. and not in excess of 800° C. as distinguished from high temperature tars produced by the carbonization of 15 coal at from 1000° to 1200° C. as in the usual by-product coke oven practice.

In accordance with my invention low temperature tar is subjected to fractional distillation under a vacuum, preferably a high vacuum, for example a vacuum corresponding to an absolute pressure of not over about 75 mm. of mercury. In carrying out my process it is found that as the temperature of distillation under vacuum and the amount of the tar removed as distillate 20 is increased, the differences in the characteristics of the distillate from corresponding fractions obtained by atmospheric distillation become more pronounced. In general, fractions of the distillate coming over at temperatures above about 25 20° C. under high vacuum are much more viscous and of higher specific gravity than corresponding fractions obtained by distillation of low temperature tar at atmospheric pressure. A striking characteristic of the higher boiling products obtained by my process is the resinous 30 nature thereof. This resinous characteristic of my new products is apparent in those fractions obtained after about 35% by volume of the tar has been removed as low boiling distillate, and as discussed in greater detail hereinafter, the last fraction of the distillate is of a distinctly resinous 35 character.

In carrying out the distillation of low temperature tars at atmospheric pressure the volume of the distillate obtained is limited by the tendency of the pitch to coke. In employing my process, the temperatures at which distillation occurs are considerably lower so that coking of the pitch 40 does not occur so readily and about 80% by volume of the tar can be obtained as distillate. Thus I not only obtain new products by my process but the amount of the tar obtained as valuable distillate is materially increased.

In order that my process may be clearly understood and the products contrasted with those obtained by the distillation of low temperature tars under atmospheric pressure, the following comparison is given. The same tar was used in each case and fractions of about equal percent by volume of the tar were collected in order that the fractions obtained in each instance would correspond as nearly as possible to each other.

10 *Distillation at atmospheric pressure*

	Percent of tar by vol.	Temp. of vapor	M. P. of residue (pitch)	Sp. gr. of oil at 15.5° C.
15 Water.....	1.55			
Light oil.....	1.92	to 205° C.		.888
Middle oil.....	32.90	205-318° C.	56° C.	.970
Heavy oil.....	26.70	318-336° C.	118° C.	1.035
Extra hy. oil.....	5.73	336-365° C.	195° C.	1.059
Resins.....	None			
20 Pitch (by diff.).....	31.20			

The boiling point ranges given in the above table and recited throughout the application refer to thermometer-in-vapor temperatures.

25 *Vacuum distillation*

	Percent of tar by vol.	Temp. of vapor	Abs. pressure in mm. of Hg	M. P. of residue (pitch)	Sp. gr. of oil at 15.5° C.
30 Water.....	0.9				
Light oil.....	2.1	to 105° C.	71		.888
Middle oil.....	32.0	105-203° C.	24	56.5° C.	.972
Heavy oil.....	26.6	203-277° C.	24	98° C.	1.061
Extra hy. oil.....	5.6	277-296° C.	27	100° C.	1.091
Resins.....	12.7	296-315° C.	11	150° C.	1.132
Pitch (by diff.).....	20.1				

40 In the above table the melting points of the pitch residue, after the removal of the first fraction or light oil, were not determined as the distillate amounted to only about 2% of the tar and the residue in each instance was fluid at atmospheric temperature. No fraction corresponding to the resins produced by vacuum distillation was obtainable from the low temperature tar when distilled at atmospheric temperatures because of the formation of coke on further heating.

45 The viscosity of the middle, heavy and extra heavy oil fractions in the above table when determined with the Engler viscosimeter is as follows:

	Sp. gr. at 15.5° C.	Temp. at which viscosity taken ° C.	Vol. of sample, cc.	Time of outflow, sec.
55 Atm. middle oil.....	0.970	25	200	78.7
Vac. middle oil.....	.972	25	200	85.5
Atm. heavy oil.....	1.035	40	50	58.5
60 Vac. heavy oil.....	1.061	40	50	254
Atm. extra heavy oil.....	1.059	80	50	29.0
Vac. extra heavy oil.....	1.091	80	50	171

65 It will be noted that the specific gravity of the heavy oil and extra heavy oil fractions obtained by distillation under vacuum is considerably greater than that of the corresponding fractions obtained by distillation under atmospheric pressure. The viscosity and resinous characteristics of these fractions are also much greater in the case of the products obtained by vacuum distillation.

70 One of the most outstanding characteristics of the low temperature tar distillates produced by vacuum distillation is their freedom from or com-

paratively low content of high boiling crystalline compounds. This property of my new products is in striking contrast with distillates obtained by the vacuum distillation of tars produced by the distillation of coal at high temperatures. This freedom from crystals characterizing my new products is a highly desirable property for products which are to be used as rubber softeners.

The middle and heavy oil fractions obtained by distillation under a high vacuum both contain substantial quantities of tar acids probably of a complex composition. A typical sample of the middle oil fraction has been found to contain 37% by volume of tar acids and a heavy oil fraction contains 27% by volume of tar acids. Such middle oil fractions containing substantial quantities of tar acids have been found to range in specific gravity from about 0.90 to 1.00 at 15.5° C.

The heavy oil fraction has a specific gravity considerably higher than the corresponding fraction obtained by distillation at atmospheric temperatures. The extra heavy oil fraction is not only of higher specific gravity but is resinous and rubbery in character and will scarcely flow at room temperature.

25 The resins produced as a final fraction when vacuum distillation is employed are tough but can be made pliable by warming in the hands. When so warmed, the resin takes on a rubber-like consistency in that it can be stretched to a considerable extent without breaking. An outstanding feature of the resins produced is their freedom from crystalline substances. This freedom from crystals is a highly desirable characteristic distinguishing the resins obtained by my process from products obtained from high temperature tars. I have found that this property of my resins renders them particularly suitable as materials to be used as rubber softeners, as specifically disclosed and claimed in my copending application Serial No. 486,279, filed October 3, 1930, now U. S. Patent 2,001,176. The new resins of my invention are also suitable for use in varnishes, lacquers, molded resinous compositions, etc. Low temperature tar distillates produced according to my process when used in rubber compounding are also superior to high temperature tar distillates in that they impart desirable characteristics to the rubber without producing the undesirable bloom resulting from the use of resin derived from high temperature tar.

40 The resinous product obtained as a final distillate in my process has a softening point varying from about 40° C. to 60° C. or even higher, depending upon the temperature at which the fraction is taken. The specific gravity of the final fraction may vary from 1.09 to 1.132 at 15.5° C. or somewhat higher. When distilling with a vacuum of about 25 mm. of mercury, it has been found that a typical low temperature tar yields about 20% of resinous distillate within a temperature range of 277° to 315° C. This product has a softening point of about 52° C. as determined by the cube-in-water method. When this portion of the distillate is collected in two fractions, the product distilling over between 296° C. and 315° C. has a softening point of 60° C. and a specific gravity of 1.132 at 15.5° C.

45 The resins produced by my process are soluble in various solvents and particularly adapted for use as an ingredient in varnishes, lacquers and stains. When dissolved in toluene the product forms a smooth film having exceptional weather resisting properties.

The fusible nature of the resinous product renders it suitable for use in molded articles either by itself or in combination with other resins, gums, fillers and similar materials employed in the manufacture of molded products.

5 The fractions in the above table are taken arbitrarily but it is evident that fewer or a greater number of fractions may be taken and the temperatures at which the successive fractions are 10 collected may be varied as desired. The degree of vacuum to be employed in distilling the low temperature tar also may be varied and will depend largely upon the character of the product desired.

15 While a preferred method of treating low temperature tar has been described, and a specific example cited, it is not intended that the invention should be limited to the treatment of such materials under the specific conditions disclosed 20 which are merely illustrative of the invention, nor is it considered that the invention is limited to the production of low temperature coal tar fractions collected at the specific temperatures suggested.

25 I claim:

1. As a new product, a distillate obtained by the condensation of vapors coming off within the range of 275° to 315° C. in the distillation of low temperature coal tar under pressure substantial-

ly less than atmospheric, said distillate being substantially free from high boiling crystalline compounds, said distillate having a specific gravity of about 1.09 to 1.13 at 15.5° C. and a softening point of from 40° to 60° C.

2. As a new product, a distillate obtained by the condensation of vapors coming off within the range of 275° to 315° C. in the distillation of low temperature coal tar under pressure substantially less than atmospheric, said distillate being substantially free from high boiling crystalline compounds, said distillate having a specific gravity of about 1.09 to about 1.13 at 15.5° C., a softening point of from 40° to 60° C., and said distillate being of a resinous consistency as distinguished from 15 an oily or waxy consistency.

3. As a new product, a distillate obtained by the condensation of vapors coming off within the range of 275° to 315° C. in the distillation of low temperature coal tar under pressure conditions 20 such that decomposition of the oil content of the tar is minimized, the said distillate having a softening point of from 40° to 60° C., a specific gravity of from about 1.09 to about 1.13 at 15.5° C. and said distillate being substantially free of high 25 boiling crystalline compounds, and being of a resinous consistency as distinguished from an oily or waxy consistency.

FRANK H. BERGEIM.
